(57) **CLAIM**

The ornamental design for a jewelry rack, as shown and described.

DESCRIPTION

FIG. 1 is a front and top perspective view of a jewelry rack, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged perspective view of detail "9" identified in FIG. 2.

The dash dot dash broken lines in FIGS. 2 and 9 represent the bounds of the enlargement taken from FIG. 2 and form no part of the claimed design.
